UNITED STATES PATENT OFFICE.

JOHN M. ROHLFING, OF PLAINFIELD, NEW JERSEY, ASSIGNOR TO AMERICAN CAR AND FOUNDRY COMPANY, OF NEW YORK, N. Y., A CORPORATION OF NEW JERSEY.

SUPPORT.

Application filed July 1, 1921. Serial No. 481,987.

To all whom it may concern:

Be it known that JOHN M. ROHLFING, residing at Plainfield, in the county of Union and State of New Jersey, and being a citizen 5 of the United States, has invented certain new and useful Improvements in a Support, of which the following is a full, clear, and exact description, such as will enable others skilled in the art to which it appertains to 10 make and to use the same, reference being had to the accompanying drawings, which illustrate the preferred form of the invention, though it is to be understood that the invention is not limited to the exact details 15 of construction shown and described, as it is obvious that various modifications thereof within the scope of the claims will occur to persons skilled in the art.

In said drawings:

20 Figure 1 is a section of my improved device taken on the line 1—1 of Fig. 2, partly broken away; and

Figure 2 is a section taken on the line 2—2 of Fig. 1.

25 It is the object of my invention to provide an improved means for supporting both the operator and the tool operated where scaffolding would otherwise be necessary for their support and it is also an object of my 30 invention to provide a support of such a nature that the positions of the operator and the tool may be readily changed both with respect to the work and to each other.

In the embodiment of my invention shown 35 in the drawings, 1 designates a suitably braced rectangular frame or member supported at its ends upon wheels 2 adapted to travel upon rails 3 mounted on girders 4 carried by a frame 5. The frame 5 may be 40 the metal frame of a building or, as where applied to the building of cars, the frame 5 may be a separate frame spanning one or more tracks, and providing an opening in which the cars, indicated by the dot and dash outline, may be placed to be operated 45 on by the tool carried by the frame.

A motor 6, mounted on the frame 1, serves, through a connection not shown, to operate the wheels 2 to move the frame 1 back and forth.

50 Secured to the frame 1 near its ends are the vertically arranged channel members 7, the pairs of channels at each end of the frame 1 being connected by channels 8 at the lower ends and by suitable bracing. The

members 7 serve as guides for a rectangular frame or member 9 supported on cables 10 that pass over pulleys 11, carried by the members 7, and are secured to a winding drum (not shown) operated by the motor 12 60 mounted upon the frame 1. Operation of the motor 12 will, therefore, operate the winding drum and raise or lower the frame 9. Extending lengthwise of the frame 9 are the parallel I-beam members 13, 14 65 and 15.

Supported on the frames 16, which are attached to carriages 17 traveling on the I-beams 13 and 15, is the operator's platform 18. A carriage 19 traveling on the 70 I-beam 14 has swiveled thereto the rod 20 upon which is mounted the vertically adjustable frame 21 in which the tool motor 22 is pivotally supported.

The motors 6, 12 and 22 for operating the 75 frames 1 and 9 and the tool 23 may be of any desired type but are shown as electric motors in the drawings. The current for the motors is supplied by means of conductors 24 and 25 carried upon insulating supports 26 secured to the girder 4. Brushes 27, which engage the conductors 24 and 25, are connected to the conductors 28 and 29 which lead to the controlling means for the various motors, the controlling means for 80 motor 6 being indicated diagrammatically by the switch 30 and the conductors 31 and 32; the controlling means for the motor 12 by switch 33 and the conductors 34 and 35; and the controlling means for motor 22 by 85 switch 36 and the conductors 37 and 38. The switches 30, 33 and 36 are mounted on the frame work supporting the operator's platform 18 convenient to the operator and the circuits are arranged to permit of the movement of the supporting frames 1 and 9, the tool carriage 19 and the operator's platform 18 without interrupting the circuits. 95

What I claim is:

1. An adjustable tool support comprising 100 a stationary frame, a horizontally movable member supported thereon, a vertically movable member carried by said horizontally movable member and comprising horizontal tracks and a tool carrying frame and an 105 operator's platform suspended from said tracks for movement independently of each other horizontally toward and from and past each other.

2. An adjustable tool support comprising 110

a frame, a member movably supported on said frame and comprising horizontal tracks, a tool carrying frame adjustably suspended from one of said tracks and an operator's platform suspended from others of said tracks for independent horizontal movement toward and from and past each other.

3. An adjustable tool support comprising a stationary frame, a horizontally movable member supported thereon, a vertically movable member supported from said horizontally movable member and comprising horizontal tracks, a tool supporting carriage carried by one of said tracks, a tool supporting frame adjustably mounted on said carriage, a tool operating motor pivotally mounted in said tool supporting frame, and an operator's platform suspended from others of said tracks for movement independently of said tool supporting carriage toward and from and past said carriage.

4. An adjustable tool support comprising a movably supported member, a second member movably supported on said first member,

a tool carrying frame and an operator's platform supported on said second member for movement independently of each other, operating means for said members and tool and controlling means for said operating means movable with said operator's platform.

5. An adjustable tool support comprising a stationary frame, a horizontally movable member carried thereon, a vertically movable member carried by said horizontally movable member, a tool carrying frame and an operator's platform mounted on said vertically movable member for independent movements thereon, operating means for said movable members and controlling means for said operating means movable with said operator's platform.

In witness whereof I have hereunto set my hand in the presence of two witnesses.

JOHN M. ROHLFING.
